UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL CONNECTER DEVICE.

Application filed February 10, 1923, Serial No. 535,492. Renewed September 4, 1925.

My invention relates to electrical connector devices and more particularly to shock-absorbing means for supporting a lamp socket.

A shock-absorbing socket is especially desirable in places where the vibration is excessive, as the excessive vibration would cause the lamp filament to be destroyed unless means were provided to absorb the vibration.

One of the objects of my invention is to provide a shock-absorbing element which may readily be interposed between a support and a lamp socket member, and which will conform to the construction of the lamp socket member.

A further object of my invention is to provide improved shock-absorbing means for supporting a lamp socket of the type in which the socket is mounted on a plate secured to the end of an electrical conduit.

A further object of my invention is to provide an improved shock-absorbing lamp socket which will be durable and efficient in use, simple in construction, and cheap to manufacture.

Further objects will appear from the detailed description to follow and from the appended claims.

In the drawings in which an embodiment of my invention is shown:

Figure 1 is a part sectional, part elevational view of a shock-absorbing lamp socket and associated parts;

Fig. 2 is a part sectional, part elevational view on an enlarged scale of the socket, the section being on the line 2-2 of Fig. 3.

Fig. 3 is a bottom plan view of the shock-absorbing device or element, which also carries the wiring terminals;

Fig. 4 is a top plan view of the lamp socket member;

Fig. 5 is a top plan view of the shock-absorbing element or member;

Fig. 6 is a section on the line 6-6 of Fig. 5; and

Fig. 7 is a section on the line 7-7 of Fig. 5.

The construction shown in the drawings comprises an electric lamp socket 10, a conduit 11 through which the wires lead to the socket 10, and which serves to support the socket 10, a metal supporting plate and clamping member 12, secured to the end of

the conduit 11, a shock-absorbing means 13 for supporting the socket 10 on the plate 12, a shade 14 for the lamp 15, and a clamping member 16 between which and the member 12 the flange 17 at the upper end of the shade 14 is clamped.

The socket 10 comprises shell and center contacts 18 and 19 respectively, mounted on a lower insulating base 20, wiring terminals 21 and 22 for the shell and center contacts respectively, mounted on an upper insulating base 23, and a pair of screws 24 and 25 for securing the insulating bases 20 and 23 together and electrically connecting the socket contacts 18 and 19 with their respective wiring terminals. The screw 24 passes through registering openings 26 and 27 in the bases 20 and 23 respectively, and is threaded into an anchor plate 28 as indicated in Fig. 5. The wiring terminal 21 is electrically connected with the anchorage member 28 and held in position on the base 23 by means of a screw 29 inserted through the anchorage member 28 and insulating base 23, and threaded into the binding terminal 21 as indicated in Fig. 3.

The screw 25 extends through registering openings 30 and 31 in the insulating bases 20 and 23 respectively, and is threaded into an anchorage member 32 as indicated in Fig. 5. The wiring terminal 22 is held in place and electrically connected with the anchorage member 32 by means of a screw 33, extending through the anchorage member 32 and the insulating base 23 and threaded into the binding plate of the wiring terminal 22 (Fig. 3).

The wires 34 lead through a central opening 34a in the insulating base 23 and are connected to the binding screws of the wiring terminals 21 and 22 respectively. The circuit is from the wiring terminal 22, through the screw 33, anchorage plate 32, screw 25, center contact 19, lamp circuit, shell contact 19, screw 24, anchor plate 28, and screw 29 to the binding plate of the wiring terminal 21.

Coming now to the shock-absorbing means for supporting the socket, these comprise oppositely acting spring means, acting between the supporting plate 12 and the socket 10, one pair of springs tending to force the socket away from the plate 12, and the other

set of springs tending to force the socket toward the plate 12, the socket thus being held in a state of yielding equilibrium between the two sets of oppositely acting springs.

The pair of springs 35 which tend to force the socket 10 toward the supporting plate 12 are mounted on a pair of screws 36, threaded into the supporting plate 12, the 10 springs 35 being located in suitable recesses in the upper insulating base 23. In order to provide a bearing for the lower end of the spring 35, an eyelet 37 is provided, the screw 36 being inserted through this eyelet 37 and 15 threaded into the plate 12.

The eyelet 37 not only serves to support the lower end of the spring 35, but also provides a smooth sliding surface for the insulating base 25 at the point where the 20 eyelet extends through the opening in this base, and further serves to determine the exact distance which the screw 36 is screwed into the supporting plate 12.

The pair of springs 38 which tend to force 25 the socket away from the supporting plate 12 are mounted to surround a pair of eyelet members 39, each spring bearing at its lower end on the insulating base 23, and its upper end on the flange of the eyelet. The 30 eyelets thus act as bearing members for engaging the supporting plate 12 and as retaining members for the springs 38. Thus, by means of two sets of springs, the socket is 35 held in counterbalanced position so that the vibration of the supporting plate 12 will not be transmitted to the socket.

It will be seen that the construction comprises broadly a support 12, a lamp socket member, and shock-absorbing device (substantially the entire construction shown in Fig. 6) interposed between the support and the lamp socket member, and having substantially the same diameter as the lamp socket member, this shock-absorbing device 40 comprising a base on which is mounted counterbalanced spring means whereby the socket is yielding held in equilibrium between the oppositely acting spring forces so that the vibration of the support will not 45 be transmitted to the socket member.

Having thus described my invention, what I claim as new and desire to secure by Letters Patent of the United States is:

1. A supporting member, a cylindrical 55 lamp socket member, and a cylindrical shock-absorbing device interposed between said support and socket member, said shock-absorbing device comprising a cylindrical base having a recess in its upper face, a 60 compression spring seated in said recess acting to push said base away from said support, said base having a recess in its lower face, and compression spring seated in said recess, acting to force said base toward said 65 support.

2. A supporting member, a cylindrical lamp socket member, and a cylindrical shock-absorbing device interposed between said support and said lamp socket member, said shock-absorbing device being coaxial with said lamp socket member, and having substantially the same diameter, said shock-absorbing device being provided with oppositely acting balanced spring means serving to yieldingly support said lamp socket member, said shock-absorbing device comprising an insulating base having a recess in its lower face, a member extending from said support and having its head located in said recess, and said spring means comprising a compression spring in said recess acting between the head of said headed member and the upper wall of the recess.

3. A shock-absorbing lamp socket construction comprising a lamp receptacle construction including an insulating base and a lamp receptacle contact mounted on said base, a supporting member, and a shock-absorbing and wiring terminal device interposed between said insulating base and support, said interposed device comprising an insulating member and a wiring terminal for the lamp contact mounted on said insulating member, spring means acting between said device and support tending to resist movement of said device away from said support, and spring means acting between said device and support tending to resist movement of said device towards said support.

4. A shock-absorbing lamp socket construction comprising a lamp receptacle construction including an insulating base and a lamp receptacle contact mounted on said base, a supporting member, and a shock-absorbing and wiring terminal device interposed between said insulating base and support, said interposed device comprising an insulating member and a wiring terminal for the lamp contacts mounted on said insulating member, and spring-shock absorbing means acting between said device and support for yieldingly supporting said lamp receptacle construction and interposed device.

5. A shock-absorbing socket construction, comprising a support having means for securing it to a conduit, a receptacle construction comprising a two-part insulating base, the two parts of which are contiguous and separable substantially on a transverse plane, a receptacle contact mounted on one of said base parts, a wiring terminal mounted on the other of said base parts and housed by and between said base parts and accessible for wiring when the base parts are separated, and means for yieldingly supporting said two-part base on said support, comprising shock-absorbing means mounted on and carried by the base part on which the wiring terminal is mounted, said wiring terminal

base part being apertured for the passage of the wire from said conduit to said wiring terminal.

6. A shock-absorbing socket construction, comprising a support having means for securing it to a conduit, a receptacle construction comprising a two-part insulating base, the two parts of which are contiguous and separable substantially on a transverse plane, a receptacle contact mounted on one of said base parts, a wiring terminal mounted on the other of said base parts and housed by and between said base parts and accessible for wiring when the base parts are separated, and means for yieldingly supporting said two-part base on said support, comprising shock-absorbing means mounted on and carried by the base part on which the wiring terminal is mounted, said wiring terminal base part being apertured for the passage of the wire from said conduit to said wiring terminal, said shock-absorbing means comprising eyelets slidably mounted on said wiring terminal base part, springs surrounding said eyelets, and screws extending through said eyelets and secured to said support.

7. A shock-absorbing socket construction, comprising a support having means for securing it to a conduit, a receptacle construction comprising a two-part insulating base, the two parts of which are contiguous and separable substantially on a transverse plane,

a receptacle contact mounted on one of said base parts, a wiring terminal mounted on the other of said base parts and housed by and between said base parts and accessible for wiring when the base parts are separated, and means for yieldingly supporting said two-part base on said support, comprising shock-absorbing means mounted on and carried by the base part on which the wiring terminal is mounted, said wiring terminal base part being apertured for the passage of the wires from said conduit to said wiring terminals, said shock-absorbing means comprising a plurality of springs mounted on said wiring terminal base part and spaced circumferentially about the axis thereof.

8. A shock absorbing socket for delicate electrical apparatus comprising a tubular member to be secured to the nipple for the feed wires and provided with an outwardly extending shade supporting flange, a wiring base having a wiring terminal thereon, means for yieldingly supporting said wiring base from said flange, a sub-assembly comprising (1) an insulating base, and (2) a receptacle contact mounted thereon, and means for securing said sub-assembly to said wiring base and electrically connecting said receptacle contact with said wiring terminal.

In witness whereof, I have hereunto subscribed my name.

REUBEN B. BENJAMIN.
